UNITED STATES PATENT OFFICE.

CHARLES N. CARLSON, OF VIRGINIA, MINNESOTA.

STORM-SASH FASTENER.

Application filed March 4, 1926. Serial No. 92,109.

This invention relates to storm sash fasteners and has particular reference to such a device operable by the window sash adjacent the storm sash.

5 The principal object of the invention is to provide a practical and efficient device of this character and one which may be disconnected with a minimum of effort.

Other objects and advantages of the invention will appear in the further description thereof.

Referring now to the accompanying drawing forming part of this application, and wherein like reference characters indicate 15 like parts:

Figure 1 is a vertical section of the lower portion of an ordinary two light window, with a storm sash applied thereto, and illustrating the application of the fastener;

20 Figure 2 is a reduced similar view showing the storm sash open; and

Figure 3 is an enlarged perspective view of the fastener.

25 Figure 4 is a perspective view of the spring clip.

1 represents the lower sash of a common window, and 2 the upper sash thereof, while 3 represents the storm sash, which swings from the upper end thereof as is common, and 4 is the sill of the window frame.

The invention simply comprises the connecting or operating rod 5, having a hole in either end, and at the upper end having the T-shaped angular bracket 7 pivotally fixed 30 thereto as at 8. A pair of elongated holes 9 are provided in the bracket 7 through which the screws are inserted for making the bracket secure to the storm sash, as indicated in Figure 1. A bracket 6, identical 35 with the bracket 7, is provided for the lower end of the rod 5, it also being provided with elongated holes 10 by which it is made secure by screws or other fastening means to the lower sash 1. It is desirable to have the 40 lower connection of the rod 5 with the bracket 6 easily disengaged, for example when the storm windows are removed in the

spring, etc., and, for this purpose, I have shown the short length of spring steel 11 fixed to the lower end of the rod 5, as indicated in Figure 3, it being bent as indicated at 12 so that the free end thereof normally is spaced from the free end of the rod 5 a distance equal to the thickness of the bracket 6. Integrally formed with the portion 11 is 55 a pin 13 which is designed to pass through registering holes in the bracket 6 and the end of the rod 5 and to form a pivotal connection therefor. Thus when the device is 60 assembled as shown in Figure 3, by manually raising the free end of the spring clip 11 withdrawing with it the pin 13, the rod 5 may be easily and quickly freed from the bracket 6 when desired.

I have shown the holes 9 and 10 elongated 65 or slot-like to provide adjustment when necessary, for example, if the lowering of the window 1 did not completely close the storm window, the bracket 6 could be lowered slightly, or the bracket 7 raised, which would 70 provide sufficient take-up so that the lowering of the window would close the storm sash.

It is obvious that other forms of removable pivotal connection may be employed, 75 and other various modifications resorted to without departing from the spirit of the invention.

Having thus described my invention, what I claim and desire to secure by Letters Patent, 80 is:

The combination with the lower sash of a window and a storm sash therefor, of vertically adjustable brackets secured to the window and storm sash, and an operating rod 85 pivotally connected at both ends to the brackets, the lowermost pivotal connection comprising a pivotal pin carried upon a spring clip for registration with the holes in the lowermost bracket and the end of the 90 operating rod.

In testimony whereof I hereunto affix my signature.

CHARLES N. CARLSON.
